(57) CLAIM

I claim the ornamental design for a shotgun forend, as shown and described.

DESCRIPTION

FIG. 1 is a bottom-left-perspective view of a shotgun forend showing my new design;

FIG. 2 is a top-left-perspective view thereof;

FIG. 3 is a first cross-sectional view thereof;

FIG. 4 is a second cross-sectional view thereof;

FIG. 5 is a third cross-sectional view thereof;

FIG. 6 is a fourth cross-sectional view thereof;

FIG. 7 is a bottom plan view thereof;

FIG. 8 is a top plan view thereof;

FIG. 9 is a left-side elevation view thereof;

FIG. 10 is a right-side elevation view thereof;

FIG. 11 is a front elevation view thereof; and,

FIG. 12 is a back elevation thereof.
